UNITED STATES PATENT OFFICE.

FRANCIS J. DOHERTY, OF CAMDEN, NEW JERSEY.

ANNUNCIATOR.

1,174,129.

Specification of Letters Patent. Patented Mar. 7, 1916.

Application filed June 3, 1915. Serial No. 31,834.

To all whom it may concern:

Be it known that I, FRANCIS J. DOHERTY, a citizen of the United States of America, and a resident of Camden, in the county of 5 Camden, State of New Jersey, have invented a certain new and useful Improvement in Annunciators, of which the following is a true and exact description, reference being had to the accompanying drawings, which form a part thereof.

My present invention is an improved electrical annunciator of the type in which a movable indicating target or "drop" is shifted from a normal position into an indicating position on the energization of an electromagnet, and the object of my invention is to provide an improved device of the type specified, characterized on the one hand by its simplicity and inherently low 15 cost of manufacture, and on the other hand by its positive action, and freedom from liability of getting out of adjustment or repair.

The various features of novelty which 25 characterize my invention are pointed out with particularity in the claims annexed to and forming a part of this specification. For a better understanding of the invention, however, and the advantages possessed 30 by it, reference should be had to the accompanying drawings and descriptive matter in which I have illustrated and described a preferred embodiment of my invention.

Of the drawings: Figure 1 is a front elevation of an annunciator mechanism embodying my invention; Fig. 2 is a side elevation of the apparatus shown in Fig. 1; Fig. 3 is a side elevation, partly in section on the line 3—3 of Fig. 1; Fig. 4 is a perspective view of the apparatus shown in Fig. 1; and Fig. 5 is a section on the line 5—5 of Fig. 3.

In the drawings I have shown a single annunciator drop with its energizing magnet mounted on vertical standards S such as are commonly employed in annunciator boxes, or casings ordinarily with a plurality of drops and magnets mounted on each of the one or more pairs of standards contained in each box or casing. As shown, a sheet metal plate C, forming or secured to the front end of the spool of the horizontal electromagnet A, is provided with ears C' through which pass screws by which the 55 magnet A is secured to the standards S. The front plate C is also formed with a pair

of bracket ears C² which are parallel to one another and to the axis of the coil A. The armature B is pivotally connected to the end of the magnet core A' projecting at the 60 rear end of the magnet.

B³ represents the pivotal connection between the armature and magnet core, and A² represents a sleeve of non-magnetic material surrounding the projecting end of the 65 armature core and holding the armature B out of direct contact therewith. The armature B is U-shaped, and the front arm B' of the armature which extends up between the ears C², is provided with horizontal pin like 70 projections B² which normally rest in the lower ends of deep notches C³ formed in the upper edges of the ears C². The projections B² also extend through the similar slots e in the similar side wings of the target or drop 75 E. As shown, the latter is formed of sheet metal having its ends bent to form the two similar parallel back turned wings in which the slots e are formed, while the central portion of the drop E forms a seat against 80 which a number bearing shield or other display member F may be secured, as by the integral lugs E' and E². The member E is pivotally connected to the wings C² by the pivot pin D passing through the ears C² 85 and the side wings of the member E.

The slots e in the member E are shaped to provide shoulders e³ which normally abut against the projections B² of the armature B and hold the drop E in the position 90 shown in Figs. 1, 2 and 4. In this condition of the apparatus the projections B² are at the bottoms of the notches C³ in the bracket ears C². When the magnet A is energized, the arm B' of the armature is lifted, and 95 the projections B² are moved out of engagement with the shoulders E³, and the drop E is free to turn into the position shown in Fig. 3. The drop E is so arranged that when freed by the energization of the magnet A as described, gravity tends to move it into the position shown in Fig. 3. It has been found, however, that with light weight and relatively inexpensive types of drops heretofore employed, that there is a frequent tendency for gravity actuated drops to stick from time to time in their elevated positions, especially as the parts are apt to become bent slightly out of shape. Such failure to operate is absolutely prevented 100 with my drop by the engagement of the projections B² with the walls of the slots e first

along the edges e' and then along the edges e^2 , and the consequent camming of the drop E into the position shown in Fig. 3. This camming action is made the more effective and certain when the magnet E is connected in series with an electric call bell, as is usually the case. When so connected, the energizing circuit through the winding of the electromagnet A is rapidly interrupted and reestablished during the period in which the bell is sounded. In consequence, the armature imparts rapidly recurring blows directly against the walls of the slot e which are very effective in preventing all tendency of the annunciator drop to stick. After the drop has assumed the position shown in Fig. 3 and the magnet is deenergized, the armature B assumes its normal position shown in dotted lines in Fig. 3. In this condition of the apparatus the projections B^2 of the armature B are received in the tail portions of the slots e which are elongated sufficiently to permit the ends of the projections B^2 to enter the notches C^3 as they do in Figs. 1, 2 and 4.

The drop may be restored to its normal position shown in Figs. 1, 2 and 4 by any usual or suitable means. As shown, the restoring means comprises a vertically movable bar T mounted in brackets S' on one of the bars S and provided with a cross pin T' adapted to engage the edges of the side wings of the member E and thereby cam the latter back into the position shown in Figs. 1, 2 and 4 in which it is then locked by the engagement of the armature projections B^2 with the shoulders e^3 of the apertures e .

It will be apparent to those skilled in the art that my improved annunciator, while simple in construction and made of a small number of parts, is positive and reliable in operation. Not only is practically all tendency of the drop to stick eliminated, but the engagement of the shoulders e^3 by the armature projections B^2 , when the latter rest in the notches C^3 in the normal condition of the apparatus, insures against the drop working loose under any vibration to which the annunciator will be subjected in ordinary use. This is a matter of practical importance when the annunciator is subjected to considerable vibration as is the case when mounted on ship board. My annunciator is also especially adapted for use on ship board or in other conditions in which it is subjected to much vibration by the fact that it contains no screws or springs liable to work loose or get out of adjustment.

While in accordance with the provisions of the statutes I have illustrated and described the best form of my invention now known to me, it will be apparent to those skilled in the art that changes can be made in the form of my invention without departing from its spirit, and that some features of

my invention can be used without a corresponding use of other features of the invention.

Having now described my invention, what I claim as new and desire to secure by Letters Patent, is:

1. In an electromagnetic annunciator, the combination with a movable drop mounted to turn about a pivotal axis comprising a portion extending transversely to said pivotal axis and formed with an aperture providing a passage through said portion in a direction parallel to said axis, said aperture being so shaped that said armature member when deenergized may engage the wall of the aperture to hold the drop in its normal position, and when energized will engage the wall of said aperture and positively move the drop out of its normal position.

2. In an electromagnetic annunciator the combination with an electromagnet and its movable armature member, of a drop comprising a sign carrying body and back turned wings pivotally supported to turn about an axis passing through said wings and in front of and transverse to the axis of the electromagnet and formed with apertures receiving portions of said armature member, said apertures being shaped to provide shoulders normally engaged by said armature member to thereby hold said drop in its normal elevated position and with edges engaged by said armature member when the magnet is energized to positively turn said drop out of its normal position.

3. In an electromagnetic annunciator, a horizontal electromagnet, a drop having back turned wings each formed with a slot, pivotal connections to said wings whereby said drop is pivotally supported to turn about a horizontal axis transverse to said wings and in front of, and transverse to the axis of said electromagnet, and an armature member pivotally supported at the rear of said electromagnet and comprising a portion extending along the under side of said electromagnet, and an upturned portion at the front of said electromagnet, said upturned portion being provided with horizontal extensions located in the space between said axis and the front end of the electromagnet and entering the slots in said wings, said slots being so formed that when said electromagnet is energized said projections may engage the edge walls of the slots and tend to move the drop from its normal elevated position into its lower sign exhibiting position, and when the drop is in its normal elevated position and the electromagnet is deenergized said projections engage the edges of said slots and hold the drop in said elevated position.

4. In an electromagnetic annunciator a horizontal electromagnet having notched bracket ears at one end, a drop formed with

back turned wings each formed with a slot, pivotal connections between said wings and bracket ears whereby said drop is pivotally supported to turn about a horizontal axis 5 transverse to said wings and in front of, and transverse to the axis of said electromagnet, and an armature member pivotally supported at the rear of said electromagnet and comprising a portion extending along 10 the under side of said electromagnet, and an upturned portion being provided with horizontal extensions located in the space between said axis and the front end of the

electromagnet and entering the slots in said wings and projecting above said bracket 15 ears, said slots being so formed that when said electromagnet is energized said projections may engage the edge walls of the slots and move the drop from its normal elevated position into its lower sign exhibiting position, and when the drop is in its normal elevated position and the electromagnet is de-energized said projections engage the edges of said slots and hold the drop in said ele- 20 vated position.

FRANCIS J. DOHERTY.
